A. EDMONDS.
HORLOGICAL CRADLE.

No. 547.

Patented Feb. 22, 1853.

Res 547

Alexander Edmonds, of Mt Pulaski, Ill.
Letters Patent No 547 dated Feb 22nd 1851.

The schedule referred to in these Letters Patent and making part of the same

To all whom it may concern

Be it known that I Alexander Edmonds of the City of Mt Pulaski and County of Logan and State of Illinois, have invented or produced a new and original ornamental design in the shape or configuration of Horological Cradles and of ornamental designs to be worked thereon and I do hereby declare that the following is full and exact description of the same reference being had to the accompanying drawings making a part of this specification. The ornamental design in the configuration of my cradle consists in forming a Bedplate of wood metal or other material, around the edge of which is a Moulding in the form of an O.G. and to the lower surface of which I attach a suitable border which hangs in a vertical position and have its lower edges ornamented by a combination of an angle semicircles and circles, etc. on the upper surface I erect two pillars one at either end. these pillars are made square and around the top another Moulding is formed in the form of a bead, to the lower surface of which is attached a border similar to the one above mentioned the top of the columns are surmounted by a ball as shown in the drawings, around the base of the Pillars there is another bead.

The body of the cradle I form in any of the known ways and suspend it by means of brackets which are formed as follows. first I form a circular ring and to the lower edge of which is attached a stem or neck which connects the ring to the other parts

of the bracket at the lower end of the stem is a cross bar running at right angles to the stem and at the end of which are suspended vertical bars which have a projection equidistant from either end. These projections are formed by drawing a line at right angles to the bar until it intersects the quadrant of a circle which is described from the point where said line intersects the bar, and said quadrant forming the upper surface of the projection while the horizontal line forms the lower surface. To the lower end of the bar to form another projection of the same length of the one just described, the upper surface of which is horizontal and the end forming a right angle to its upper surface, on the lower surface of the projection are suspended other bars which are formed in the shape of an O.G. and are joined together at their lower extremities; when I form another neck or stem to the lower end of which is attached arms also in the form of an O.G.

Which arms are attached to the body of the cradle near the centre of said arms there is a horizontal bar connecting them, in the centre and at the lower edge of which is attached other arms or bars running at an angle of 60 degrees from a perpendicular until they intersect other bars running in a contrary direction, and starting from the periphery of a circular ring. Which is attached to body of the cradle & the whole making a new and ornamental design in the configuration and shape of said Bracket.

In the Drawings

Fig 1. is a side elevation of the bridle showing the ornamental designs on the columns, and body of the bridle.

Fig 2. is a detached view of the bracket and a transverse section of the body of the cradle in the line 4-4 fig 1

The design on the column 4, Fig 1, is composed of a combination of curves and circles arranged precisely as shown

in the drawings.

The design on the column B, Fig 1 is also formed of a combination of curves and circles with the addition of vines leaves &c, but differing materially from the one at D, on the other column.

The designs on the body of the Cradle are first a star the points of which all radiate from the centre and are all encircled by a ring and directly over it is united the stems of two leaves which overhang the whole and forming one design, which is placed on the head of the cradle at C, on the body of the cradle is placed another figure consisting of two vines, running in opposite directions and leafing at intervals as shown at D and connected together at their intersections as seen in the drawing.

What I claim as my production and desire to secure by letters patent is the design and configuration of the ornaments above described and set forth forming together an ornamental design for a Horological Cradle.
